UNITED STATES PATENT OFFICE.

JOHN A. BRAKE, OF DAYTON, OHIO.

MANIFOLDING-BOOK.

SPECIFICATION forming part of Letters Patent No. 625,139, dated May 16, 1899.

Application filed February 13, 1899. Serial No. 705,400. (No model.)

To all whom it may concern:

Be it known that I, JOHN A. BRAKE, a citizen of the United States, residing at Dayton, in the county of Montgomery and State of Ohio, have invented certain new and useful Improvements in Manifolding-Books; and I do hereby declare that the following is a full, clear, and exact description of the invention, which will enable others skilled in the art to which it appertains to make and use the same, reference being had to the accompanying drawings, and to the figures of reference marked thereon, which form a part of this specification.

This invention relates to improvements in manifolding-books for use in stores and other places where it is desired to make more than one copy of orders or other memoranda. The new and essential features of the book consist, first, in the manner of attaching the carbon sheet or sheets, and, secondly, in the arrangement of the other sheets. It is customary in making manifolding or sales books to provide a ledge or raised part at one end of the book and to secure the carbon-sheets to said ledge; but heretofore the carbon-sheets have been attached to the ledge at some point above the lower plane of the sheets, or, in other words, at some intervening point between the bottom or under side of said ledge and the upper side thereof; but never, so far as I am aware, have said carbon-sheets been attached or secured beneath the bottom of said ledge. In other instances the carbon-sheets have been attached to the upper side of said ledge. The first-named way of attaching said carbon-sheets—to wit, at some point above the bottom side of said ledge—has been found objectionable on account of the continual opening and closing of the order-sheets having a great tendency to make the carbon-sheets tear off at the ledge. When the carbon-sheets are attached to the top of the ledge, their constant exposure to the air causes them to dry out and soon become useless. By attaching said carbon-sheets in the manner hereinafter described the objections named above are obviated. In books of this character much annoyance is also experienced by having the cover open in the direction of the writer and printed headings of the order-

sheets beginning at the bound ends of said sheets. This arrangement is very inconvenient, because of the constant tendency of the cover to interfere with a free movement of the writer's arm and the free ends of the order-sheets to curl up under the arm, and thus interfere with the use of the book. The book comprised in the present invention is so constructed that the above difficulties are avoided.

Figure 1 is a perspective view of a manifolding-book made in accordance with my invention, the cover being thrown back and broken away. Fig. 2 is a side or edge elevation with part of the cover broken away.

The order-sheets 1, with adjacent tissue-sheets for a third copy, are sewed or bound at the end 2 to the back 3, or the said order-sheets may be bound together at said end and constitute a filler, which may be attached to the back 3 in other ways. As is clearly shown in Fig. 1, the printed headings on the order-sheets 1 read from the free ends of said sheets. Adjacent to the free ends of the order-sheets there is a ledge 4, secured to the back 3, and between the lower side of said ledge and the back of the book one or more carbon-sheets 5 are secured. This carbon-sheet is attached on a plane coinciding with that of the extreme bottom sheet of the book. In order to bring said carbon sheet or sheets up and over the order-sheets in the position shown in the drawings or any other position above its level, it is essential that the carbon-sheets be somewhat longer than the order-sheets. The carbon sheet or sheets thus attached beneath the ledge and used in the manner described are always protected from the air, and the free ends of the sheets 1 need not come in contact with said carbon-sheets when opening and closing said sheets 1. It will be observed there is a sufficient space 6 between the free ends of the order-sheets and the ledge 4 to enable, when said carbon-sheets are drawn over the ledge in the direction of the cover, the said order-sheets to be opened and closed without coming in contact with any part of said carbon-sheets. The cover 7 is a continuation of the back 3 and closes over the ledge. The said cover, it will be noted, opens in a direction away from the writer. Therefore it

will not be in the way of the writer's arm. Also the ends of the order-sheets nearest the writer are bound, so they will not curl up.

I claim as my invention—

- 5 1. In a manifolding-book, the combination with the back and cover, of the order-sheets having ends bound to the end of said back, and their free ends adjacent to the bend of the cover, a ledge over which said cover bends, and one or more carbon-sheets secured between the lower side of said ledge and the back, the said carbon-sheets being essentially longer than the order-sheets so that they may cover the entire writing-space on said order-sheets, substantially as specified.
- 15 2. A manifolding-book, comprising order-sheets bound at one end and attached at said bound end to the back of the book, the free

ends of said order-sheets being adjacent to the attached end of the cover, and the printed headings thereon being so arranged on said sheets that the writing will be in a direction away from the said free ends, a ledge adjacent to said free ends, and one or more carbon-sheets attached between the lower side 25 of said ledge and the back of the book, and a cover for said book adapted to be opened in a direction away from the writer, substantially as described.

In testimony that I claim the foregoing as 30 my own I hereto affix my signature in presence of two witnesses.

JOHN A. BRAKE.
